UNITED STATES PATENT OFFICE

FRANK T. PELKEY, OF MARINE CITY, MICHIGAN

ANCHOR

Application filed June 26, 1929. Serial No. 373,792.

This invention aims to provide an anchor in which the stock is so connected with the head of the anchor that the flukes of the anchor will be pitched downwardly and forwardly so as to secure a good hold. Another object of the invention is to provide a two-piece anchor the constituent parts of which may be assembled and taken apart readily, without the use of tools.

10 It is within the province of the disclosure to improve generally and to enhance the utility of devices of that type to which the invention appertains.

With the above and other objects in view, 15 which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

In the accompanying drawings:—

25 Figure 1 shows in plan, a device constructed in accordance with the invention; Figure 2 is a side elevation;

Figure 3 is a longitudinal section with the stock of the anchor removed;

30 Figure 4 is a rear end elevation;

Figure 5 is a front elevation, the stock having been removed and parts being in section.

The anchor forming the subject matter of 35 this application includes a head 1 from which forwardly extended and approximately parallel flukes 2 project. The head 1 is provided in its rear end with an elliptical opening 3. There is a collar 4 on the 40 head 1 around the rear end of the opening 3. The opening 3 increases in height, as shown at 5, as it extends forwardly, and the opening decreases in width, as shown at 6, as it extends forwardly, the forward end of the 45 opening being in the form of an elongated rectangle, as shown at 7, there being forwardly tapered recesses 8 within the head 3, at the sides of the opening, the recesses extending but part way through the head from 50 front to back, so that part of the constituent

material of the head remains in place in the forward and rear ends of each recess, as appears at 9.

This construction greatly enhances the hold of the stock 10 on the body portion of 55 the anchor. The stock 10 is provided at its outer end with an eye 11 and at the rear end of the stock there is a ball or sphere 12 which is received in the recesses 8. The head 1 has outstanding fulcrum flanges 14. The ball 60 12 on the rear end of the stock 10 engages in the recesses 8 at a point ahead of the flanges 14, as indicated in Figure 2, and the result is that the weight of the stock 10 tends to force the forward ends of the flukes 12 65 downwardly, as indicated by the arrow in Figure 2. The anchor, as a consequence, naturally tends to acquire a firm hold on the bottom.

Figures 1 and 2 will show that the stock 10 70 is of unequal transverse dimensions, the greater transverse dimension of the stock being the vertical dimension. The stock 10 can swing up and down, in a vertical plane, in the elongated mouth 7 of the opening in the 75 head, and although the stock can turn a very little on its axis, there is practically no axial rotation of the stock in the head 1. Because the stock 10 cannot turn on its axis, the chance of kinking or fouling the anchor line 80 is reduced, provided that the line is paid out fairly and without kinks as it runs through the hawse or through the chock.

It is to be noted that the device forming the subject matter of this application is a 85 simple two-piece anchor, and that the stock 10 can be disengaged from the head 1 by sliding the stock rearwardly in the opening 3, there being nothing in the opening which interferes with the free rearward sliding 90 movement of the stock, thereby to dispose the rear end of the stock behind, and in spaced relation to, the head, and to change the direction of the leverage of the stock on the head, and to give the rear end of the stock 95 a direct fulcrum bearing on the sea floor. This aids in freeing the anchor when it is fouled, but does not impair the holding qualities of the anchor, because when a vessel rides to the anchor, the pull is in the direc- 100

tion of the stock 10 in Figure 2. When it is desired to free the anchor, if fouled, the vessel simply is set aback, the stock 10 is slid rearwardly from the position of Figure 5 2, and the changed leverage on the sea floor, hereinbefore referred to, is attained. The construction is such that the anchor can be taken down in a very short time, without the use of tools, and be stowed in a locker in 10 which there would not be room for the anchor if it had to be stowed in the assembling condition shown in Figures 1 and 2.

What is claimed is:—

1. An anchor including a head having an 15 opening, the head being provided with forwardly extended flukes and a stock extended between the flukes and having an enlargement mounted to rock in the openings, (the cross-sectional area of the stock being less than 20 the cross-sectional area of the opening) the opening being unencumbered, to the rear of the enlargement, and being large enough at its rear end to permit the passage of the enlargement, whereby the stock can be slid 25 freely in a backward direction, when the anchor is in use, thereby disposing the rear end of the stock behind, and in spaced relation to, the head, thereby to change the direction of the leverage of the stock on the head, and 30 to give the rear end of the stock a direct fulcrum bearing on the sea floor.
2. An anchor including a head provided with forwardly extended flukes, the head having an opening located between the 35 flukes, the opening increasing in height as it extends forwardly, and the forward end of the opening being contracted in width, there being recesses within the head, at the sides of the opening, the recesses being of less area 40 than the sides of the opening and extending but part way through the head from back to front, and a stock of unequal transverse dimensions insertable through the opening and held against axial rotation in the contracted 45 forward end of the opening, the stock being provided at its rear end with a ball received removably in the recesses: the opening being unencumbered to the rear of the ball, the recesses constituting means for holding the 50 ball and the stock spaced with respect to one wall of the unencumbered opening, and the unencumbered rear end of the opening being larger than the ball to permit material, which would otherwise foul the stock and 55 prevent movement of the stock with respect to the head, to pass through the opening.

In testimony that I claim the foregoing as my own, I have hereto affixed my signature.

FRANK T. PELKEY.
